UNITED STATES PATENT OFFICE.

FRANK F. WELLS, OF KANSAS CITY, MISSOURI.

DESIGN FOR A BRACELET.

47,148.

Specification for Design.

Patented Mar. 23, 1915.

Application filed December 14, 1914. Serial No. 877,243. Term of patent 3½ years.

To all whom it may concern:

Be it known that I, FRANK F. WELLS, a citizen of the United States, residing at Kansas City, in the county of Jackson and State of Missouri, have invented a new, original, and ornamental Design for Bracelets, of which the following is a specification, reference being had to the accompanying drawing, in which—illustrates my new design. Fig. 2 is a plan view of the bracelet.

I claim—

The ornamental design for a bracelet, as shown.

FRANK F. WELLS.
